JOHN MACINTOSH AND WILLIAM BOGGETT, OF LONDON, GREAT BRITAIN.

Letters Patent No. 93,103, dated July 27, 1869; antedated July 22, 1869.

IMPROVEMENT IN BOOTS AND SHOES.

The Schedule referred to in these Letters Patent and making part of the same.

To all whom it may concern:

Be it known that we, JOHN MACINTOSH and WILLIAM BOGGETT, of London, in the county of Middlesex, and Kingdom of Great Britain, have invented certain Improvements in Shoes, &c.; and we do hereby declare the following to be a full, clear, and exact description of the same, reference being had to the accompanying drawings.

Our invention consists in the combination, with a shoe or gaiter, of certain elastic bands, arranged as fully described hereafter, so as to draw together the two sides of the "vamp" or "upper," and close the opening between them, while the bands are protected from the abrasion to which elastic bands or laces, applied in the ordinary manner, are liable.

In order to enable others skilled in the art to make and use our invention, we will now proceed to describe the construction of the same, reference being had to the accompanying drawing, which forms a part of this invention, and in which—

Figures 1 and 2 show sufficient of the uppers of a shoe and of a gaiter to illustrate our improvement;

Figure 3, the upper of a gaiter of a different pattern; and

Figure 4, a portion of the upper of a shoe, laced in the ordinary manner.

A is the "upper" or "vamp" of a shoe or gaiter, which is divided at the front, or at one or both sides, as usual, and across the opening thus formed extend elastic strips or "fillets" a, the ends of the latter being introduced between the leather and lining at the sides of the opening, as shown in dotted lines, where they are secured by stitching or otherwise.

The fillets are of such a length as to permit the sides of the "upper" to be separated sufficiently to allow the foot to be introduced or withdrawn, and so elastic as to draw together these sides after the insertion or withdrawal of the foot.

It will be seen that when the two sides of the vamp are drawn together, the fillets or bands are entirely covered, and are thus protected from the action of water and dust, and from that abrasion to which elastic laces extending over the face of the vamp, as shown in fig. 4, are liable.

One side of the vamp may overlap the other to form a flap, at the edge of which buttons are secured, as shown in the drawing, the fillets in this case being attached to the under side of the flap at a distance from the edge of the same, or to the buttons.

The fillets are in some cases made of vulcanized sheet-rubber combined with elastic fabric, or of strips of rubber covered with fibrous threads by braiding-machines. In the latter case, threads of different colors, or of different materials, as threads of silk and metal, or metallic threads alone, may be used.

Without confining ourselves to any particular form of boot or shoe,

We claim as our invention, and desire to secure by Letters Patent—

A shoe or gaiter having elastic bands or fillets applied to and connecting the opposite sides of the "vamp" or "upper," so as to be concealed when the edges of the said sides are in contact, substantially as and for the purpose described.

In testimony whereof, we have signed our names to this application, in the presence of two subscribing witnesses.

JOHN MACINTOSH.
WILLIAM BOGGETT.
